(57) **CLAIM**

The ornamental design for a lighting control faceplate, as shown and described.

DESCRIPTION

FIG. 1 is a front elevational view of a lighting control faceplate showing out new design, the rear being unornamented;

FIG. 2 is a right side elevational view thereof;

FIG. 3 is a bottom plan view thereof, the top plan view being a mirror image thereof;

FIG. 4 is a left side elevational view thereof; and,

FIG. 5 is an isometric perspective view thereof.

The broken line showing of a switch housing in FIGS. 2-5 is for illustrative purposes only.
